UNITED STATES PATENT OFFICE.

NICHOLAS J. CONRAD, OF CHICAGO, ILLINOIS, ASSIGNOR TO SCHWEITZER & CONRAD, INC., OF CHICAGO, ILLINOIS, A CORPORATION OF ILLINOIS.

LIGHTNING-ARRESTER.

1,251,754.

Specification of Letters Patent.

Patented Jan. 1, 1918.

Application filed March 30, 1917. Serial No. 158,550.

To all whom it may concern:

Be it known that I, NICHOLAS J. CONRAD, a citizen of the United States, residing at Chicago, in the county of Cook and State of Illinois, have invented a certain new and useful Improvement in Lightning-Arresters; of which the following is a full, clear, concise, and exact description, reference being had to the accompanying drawings, forming a part of this specification.

My invention relates to lightning arresters of the horn gap type and more particularly relates to an improvement upon the structure shown in patents granted to myself and

15 Edmund O. Schweitzer jointly as follows:

No. 1151726 August 31st 1915.

No. 1164757 December 21 1915.

This type of arrester is designed to effect relief from over voltages regardless of the 20 origin of the same with a minimum disturbance of the voltage on the line.

The ideal qualities for an arrester are, ability to give instant relief from over voltage but without causing disturbance upon 25 the line; ability to interrupt positively the flow of current, ruggedness and serviceability together with low cost of construction and maintenance.

It is the aim of this invention to provide an 30 improved structure for a lightning arrester having as far as possible the above qualities. Further and more specific aims will be apparent from the following specification which, together with the accompanying 35 drawings, describes and illustrates an embodiment of the invention.

Figure 1 is a side elevation of a lightning arrester constructed in accordance with my invention;

40 Fig. 2 is a fragmentary cross sectional view showing the manner of mounting the resistance members;

Fig. 3 is a plan view and Fig. 4 a side elevation of one of the spring terminals for 45 engaging the resistance members; and

Fig. 5 is an end elevation and Fig. 6 a side elevation of a form of terminal clips or mounting for engaging the other ends of the resistance members.

50 Fig. 7 is a cross section taken on line 7—7 of Fig. 1.

The arrester comprises essentially a pair of horn gap electrodes 1 and 2 which are supported in suitable relation to each other 55 upon a bar of channel iron 3. The electrode

1 is connected to the line by means of a suitable terminal 4 and the electrode 2 is connected by means of the terminal 5 to ground. A line insulator 6 of sufficient insulating capacity to safeguard the voltage of the particular line forms an insulating support for the electrode 1. The insulator 6 is mounted upon a metal pin 7 that is bolted to the channel bar 3. The top of the insulator 6 supports a cap or clamp member 8 which has bolted thereto a clamp member 9 for clamping the lower horizontal portion of the electrode 1. This electrode comprises a rectangular copper bar 10 which is presented edgewise toward the corresponding electrode 2. The electrode 1 is divided into two operating parts, namely, the converging portion 10 and the diverging portion 11. The converging portion of the electrode 1 is mounted upon a backing member 12 76 which comprises a piece of flat bar material which has a diagonal portion 13 and a horizontal portion 14, the rear end of which horizontal portion is connected to the converging part 11 of the electrode by bending 80 the upper end of the portion 11 sharply downward to form a tie 15 between the extreme upper end of the diverging portion and the supporting bar 14. A reinforcing bar 16 underlies the bar 14 and the bar 14 is clamped against the stationary bar 16 by means of the clamp member 9 on top of the insulator 6 to hold the electrode 1, in any desired position. The stationary bar 16 is fastened to the cap 8. This permits adjustment of the electrode 1 without disturbing the terminal 4.

It will be noted that at the point where the convergent portion 10 and the divergent portion 11 join each other, the electrode 1 95 approaches most closely to the electrode 2. This point indicated by reference character 17 I designate as the throat of the spark gap.

The electrode 2 is sectionalized and the sections are connected together through resistance members for limiting the flow of current. A piece of heavy iron pipe 19 is mounted by means of a flange 20 upon the channel member 3. Within the upper end of the pipe 19 is embraced an insulating column 21 which, as shown in Fig. 2, consists of a central core of impregnated wood 22 surrounded by a sleeve or facing of bakelized fiber which protects the wood from damage by the weather.

The top of the column 21 is covered by a cap member 24 of metal to the top of which is connected the divergent portion 25 of the electrode 2, the connection being made by means of the tie portion 26 formed by bending the upper end of the part 25 downward.

The electrode 2 comprises a vertical portion 26' which joins the divergent portion 25, this vertical portion 26' being broken up 10 into a plurality of independent sections comprising the circular disks 27. The uppermost disk 27 is connected by means of a short link 28 to the divergent portion 25 of the electrode 2 while the lowermost disk 27 15 is connected through a diagonal bar 29 and a horizontal bar 30 with the pipe 19 and the ground terminal 5. The intermediate terminals are connected between the above mentioned terminals through resistance members, as will be described. The circular sections or disks 27 are supported upon the outer ends of the insulating tubes 31 which are mortised into the insulating column, as shown in Fig. 2. The disks 27 are made of 20 socalled "non-arcing" metal consisting of an alloy of zinc and copper. The outer end of the insulating sleeve 31 is closed by a metallic cap 32 which embraces and binds the open end of the sleeve 31. A spring clip, 25 as is shown in Figs. 5 and 6, is electrically and mechanically secured upon the inside of the cap 32 in such position that the spring terminal 33 slides inside of the open end of the sleeve 31. The circular disk 27 is secured upon the cap 32 by means of a machine screw 34 which has a spring washer 35 held under its head in order to insure that the disk will remain clamped in place. A resistance member 36 has its ends gripped 30 in the spring clip or socket 33 and the other end of the resistance member is connected to a spring socket member 37 which is shown in detail in Figs. 3 and 4. The spring terminal 37 is formed of a cup of brass which is 35 slotted as shown in Figs. 3 and 4 at right angles as indicated at 38 and one side of each slot is depressed to form a spring finger or gripping member.

The terminal 37 is connected by means of 40 a screw 39 to a flat conductor 40 which is fastened by means of a suitable screw 41 to the cap member 32 of the next lower tube.

The outer ends of the tubes 31 are supported in proper spaced relation by means 45 of a spacing member 42 which comprises a flat piece of insulating material having suitable openings for receiving the insulating tubes 31 and other openings as shown at 43 for the flat conductors 40. The lower end of 50 the spacing member 42 is connected by a short link 44 to the diagonal member 29 which supports the lowermost disk 27 so that all of these parts are rigidly held in proper spaced relation. The lowermost terminal member 37 is connected by means of 55

a conductor 45 to the bar 30 and thus to the ground terminal 5.

It can now be seen that the terminal disks 27 are connected to each other in each case in series with a suitable resistance member 36 interposed. Due to the converging space between the electrodes 1 and 2 which has its narrowest portion at the throat 17, the tendency will be for any excess voltage to break down the air gap at the throat 17 which, 75 however, is the point of greatest circuit resistance to the passage of current. The diagonal members 13 and 29 are each provided with a spherical electrode member 46 and 47 respectively which form a convenient 80 path for the immediate relief of high frequency disturbances. These spherical electrodes are placed directly below the horn electrodes so that a discharge initiated between them will be transferred to the horn 85 electrodes and there extinguished.

The entire electrode structure 1 may be adjusted toward or away from the electrode structure 2 by loosening the clamping member 9 and sliding the bar 14 under said 90 clamping member to the desired position. Suitable pins 48 and 49 limit the adjustment of the arrester within the rating of the arrester.

The operation of the arrester is as follows: 95

The electrode 1 is at all times subject to the line potential and the potential of the electrode 2 is that of the ground. As the shortest air gap between these electrodes exists at the throat 17, the tendency will be for the discharge first to break down the air gap at this point. However, the flow of current across the throat of the arrester will experience a maximum of resistance 100 in passage to the ground. The gaps between the terminal disks 27 are so adjusted with respect to the resistance 36 that for a rise of potential which is slightly greater than that which will break down the air 105 gap at the throat 17 the current will flow in series through the resistances. If the potential is substantially greater, the current may jump across a part or all of the gaps between the terminal disks 27 and thus pass 110 to the ground terminal 5. If the current which passes across the gap at the throat 17 and in series through the resistances 36 is insufficient to relieve the excessive pressure, the arc which is formed will spread 115 downward to successive terminal disks 27 thereby finding a path to ground which contains a lesser circuit resistance because fewer of the resistance members 36 are included. As soon as the arc is formed there is tendency for the gases which are heated by the arc to cause an upward current with the consequence that the arc even if it has descended along the converging part of the gap will be driven upward. As the arc is 120 125 130

moved upward the resistance members 36 will be successively inserted in the circuit and the arc will finally be blown up along the diverging arms 11 and 25 and be broken.

5 The arc will thus always tend to be formed through a path of less break-down strength and less carrying capacity. If the capacity to discharge will not relieve the pressure a path of greater break-down strength and greater current carrying capacity will then be brought into play until the excess pressure is relieved. At the same time a tendency is created by the upward draft or current of air to confine the discharge to a path of less carrying capacity and to break the arc entirely.

10 The electrode disks 27, if they become damaged, may be readily renewed, or if damaged only at one point they may be turned so as to present a fresh surface to the adjacent disk. The disks 27 are arranged preferably in a vertical line, although it is to be understood that this arrangement is not necessary.

15 The spherical electrodes 46—47 are set back a slight distance from the line of the electrodes 1 and 2. The particular function of the spark gap formed between the spherical electrodes is to present a direct and convenient path for high frequency which gap I call a high speed gap. The high speed gap is in parallel with the main gap and presents a direct route of greater break down strength but of less impedance which 20 is particularly desirable for high frequency disturbance. Thus I have provided a series of gaps in parallel, the ones of less break-down strength having greater resistance and the one of maximum break-down strength 25 having a minimum of impedance.

The invention may appear in other forms than the particular embodiment described and illustrated.

I claim:

45 1. In an arrester, a pair of horn gap electrodes having a spark forming gap converging upward to a throat, said electrodes having each a divergent horn above the throat for breaking the arc, one of the electrodes below the throat comprising a series of short metallic sections separated from each other in the direction of the length of the electrode, substantially horizontal resistance members connected between said sections, 50 and a plurality of individual substantially horizontal supporting members each member supporting one of said metallic sections and one of said resistance members and conductors connecting the rear end of one resistance with the front of an adjacent resistance.

2. In an arrester, a pair of electrodes forming a spark gap converging upward to a throat, said electrodes having means for 55 breaking the arc, one of the electrodes be-

low the throat comprising a series of short metallic sections separated from each other in the direction of the length of the electrode, resistance members connected between said sections, a column of insulation and a 70 plurality of individual insulated supporting members connected to said column of insulation and supporting said metallic sections.

3. In an arrester, a pair of electrodes 75 forming a spark gap converging upward to a throat, said electrodes having means for breaking the arc, one of the electrodes below the throat comprising a series of circular disks placed edge to edge and resistance means connecting said disks, said disks being held with their edges out of contact.

4. In an arrester, a pair of horn gap electrodes lying in substantially a vertical plane, said electrodes having a spark forming gap 80 converging upward to a throat, said electrodes having each a divergent horn above the throat for breaking the arc, one of the electrodes below the throat comprising a series of short metallic sections separated from each other in the direction of the length of the electrodes, resistance members connected between said sections, a column of insulation and a plurality of individual insulated supporting members connected to said column of insulation and supporting said metallic sections.

5. In an arrester, a pair of horngap electrodes lying in substantially a vertical plane, one of said electrodes being supported upon an insulator and connected to the line, the other of said electrodes being supported upon a metallic post and being adapted to be connected to ground, said electrodes having a spark forming gap converging upward to 100 a throat and having each a divergent horn above the throat for breaking the arc, the outer ends of said horn being secured to the post and to the insulator respectively, one of the electrodes below the throat comprising 105 a series of short metallic sections separated from each other in the direction of the length of the electrodes, resistance members comprising horizontal rods connected between said sections, a column of insulation and a 110 plurality of individual supporting members comprising hollow rods of insulation connected to said column and supporting said metallic sections, said resistance members being disposed in said hollow rods.

6. In an arrester, a pair of horngap electrodes lying in substantially a vertical plane, one of said electrodes being supported upon an insulator and connected to the line, the other of said electrodes being supported upon 115 a metallic post and being adapted to be connected to ground, said electrodes defining a spark gap converging upward to a throat and having each a divergent horn above the throat for breaking the arc, the outer ends of 120

- 4
- said horn being secured to the post and to the insulator respectively, one of said electrodes below the throat comprising a series of short metallic sections separated from each other in the direction of the length of the electrodes, disk members comprising horizontal rods connected between said sections, a column of insulation and a plurality of individual supporting members comprising hollow rods of insulation connected to said column and supporting said metallic sections, said resistance members being disposed in said hollow rods, and means for holding said hollow rods and said metallic sections properly spaced from each other.
7. In an arrester, a supporting base, a metallic post mounted on said base, a column of insulation supported on said post, a series of rods of insulating material projecting from said post, metallic caps on the free ends of said rods, resistance means supported on said rods and connections for said resistance means and said caps to place the resistance means in series with the caps.
- 25 8. In an arrester, a supporting base, a metallic post mounted on said base, a column of insulation supported on said post, a series of rods of insulating material projecting from said post, metallic caps on the free ends of the rods, resistance means supported on said rods, and connected between individual ones of the series of caps and a ground connection on said post, said ground connection being connected in series with said resistance means.
9. In an arrester, a supporting base, a column of insulation supported on said base, a series of hollow rods of insulating material projecting from the sides of said post, metallic caps on the free ends of said rods, a divergent horn connected to the upper cap and having its free end connected to said column, resistance means lying in said rods and connections for said resistance means and caps to place the resistance means in series with the caps.
10. In an arrester, a supporting base, a column of insulation supported on said base, a series of rods of insulating material projecting from said column, metallic caps on the free ends of said rods, resistance means supported on said rods, connections for connecting the resistance means in series with the caps, and a bar of insulating material supporting the free ends of the rods.
11. In an arrester, a supporting base, a column of insulation supported on said base, a series of rods of insulating material projecting from said column, metallic caps on the free ends of said rods, resistance means supported on said rods, connections for connecting the resistance means in series with the caps, and a bar of insulating material supporting the free ends of the rods, and a series of removable disks secured on the outer ends of the caps, said disks being held out of contact with each other.
12. In combination a series of metallic disks placed edge to edge out of contact with each other, a horn electrode secured to the uppermost disk, a ground connection secured to the lowermost disk, a series of insulating rods and a column supporting said rods, said rods supporting said disks in spaced relation, and resistance means connected in series between said disks.
13. In combination, a pair of spark gap electrodes having a spark gap between them, a pair of spherical electrodes connected to said spark gap electrodes and forming a gap between them of slightly greater width than the width of the spark gaps formed by electrodes adjacent them.
14. In combination, a pair of arrester electrodes each comprising a horizontal portion and a generally vertical portion, said vertical portions forming a spark gap between them, a pair of spherical electrodes secured to said arrester electrodes adjacent the horizontal portion of each, said spherical electrodes forming a spark gap of slightly greater width than the spark gap formed between the vertical portion.
15. In combination, a pair of horngap electrodes one of said electrodes being sectionalized, resistance means connected between said sections, and a spherical terminal secured to each of said electrodes at a point below said resistance means, said spherical terminals forming between them a spark gap directly between the line and ground, said spherical terminals being so located that a discharge formed between them will be transferred to the horngap electrodes and extinguished.
16. In combination, a pair of horn electrodes, said horn electrodes having converging and diverging portions defining a throat or spark gap of minimum distance, a pair of spherical terminals connected to said electrodes, said spherical terminals being separated to form a spark gap greater than the spark gap at the throat of said electrodes and means for connecting one of the electrodes to the transmission line and means for connecting the other electrode to ground, said spherical terminals being so organized as to provide a direct path from line to ground for high frequency discharges.
17. An arrester for the dissipation of excess electrical energy composed of a multiplicity of arc extinguishing gaps, part of which gaps are made of a horn shaped member and the other part of disk shaped members, said disk shaped members being arranged in a vertical row and being independently rotatable to present fresh arcing surfaces.
18. The combination of a series of air gaps consisting of a gap formed by a horn shaped

- member in electrical circuit with a multiplicity of disk or cylindrical members, the latter having current limiting resistances at the ends opposite the air gaps, said disk or cylindrical members having their spherical surfaces adjacent to each other to form small spark gaps, said members being rotatable to present fresh arcing surfaces.
19. In combination a series of short metallic sections comprising disks placed edge to edge with their axes parallel arranged in a vertical row, said disks consisting of a non-arcning alloy of zinc and copper, a horn electrode secured to the upper disk of the series, means for supporting said disks in proximity but out of contact with each other and a ground connection for the lowermost disk, said disks being independently rotatable to present fresh arcing surfaces.
20. In combination a horn gap electrode, a series of disks, said disks comprising an arc extinguishing alloy of copper and zinc, said series of disks forming with the horn gap electrode a series of spark gaps in parallel and forming with each other a series of spark gaps in series relation, and connections for the horn gap electrode and for one of said disks, said disks being independently rotatable to present fresh arcing surfaces.
21. In an arrester, an electrode consisting of a plurality of spaced disks or cylinders arranged in a vertical row with their axes parallel and a horn shaped electrode and a second electrode forming a plurality of parallel spark gaps with said disks or cylinders and said horn shaped member, said disks being rotatable to present fresh arcing surfaces.
22. An arrester for the dissipation of excess electrical energy comprising a plurality of arc-extinguishing gaps, said gaps being formed between a common electrode and a series of separate electrodes, said series of electrodes comprising a horn shaped member and a plurality of circular disks arranged in a vertical row with their axes parallel and being individually rotatable to present fresh arcing surfaces.
23. In combination, horngap having one horn consisting in part of a plurality of cylindrical electrodes having their axes lying parallel, and having their circular edges separated to form spark gaps, a pair of electrodes having spherical faces presented toward each other, said spherical electrodes being adapted to have less breakdown resistance for certain types of disturbances and being adapted to transfer an arc after it is formed to the adjacent horn-gaps.
24. In combination, a horn electrode formed of an upper solid metal diverging horn and another part below the horn comprising a series of cylindrical electrodes arranged in a vertical row, said electrodes being spaced apart to form spark gaps between their cylindrical surfaces, said cylindrical electrodes being individually secured in rotatable manner to permit a fresh arcing surface to be presented, and a solid electrode co-operating with said horn-electrode to form a main spark gap.

In witness whereof I hereunto subscribe my name this 28th day of March, A. D. 1917.

NICHOLAS J. CONRAD.
